UNITED STATES PATENT OFFICE.

PRICE C. CLAFLIN, OF WASHINGTON, DISTRICT OF COLUMBIA.

DESIGN FOR A LENS FOR EYEGLASSES.

SPECIFICATION forming part of Design No. 26,697, dated March 2, 1897.

Application filed January 25, 1897. Serial No. 620,693. Term of patent 14 years.

To all whom it may concern:

Be it known that I, PRICE C. CLAFLIN, a citizen of the United States, and a resident of the city of Washington, in the District of Columbia, have invented and produced a new and original Design for Cataract-Lenses for Eye-glasses and Spectacles, of which the following is a specification, reference being had to the accompanying drawings, forming a part 10 thereof.

Figure I is a front elevation of a cataract-lens for eyeglasses and spectacles, showing my design. Fig. II is a longitudinal section of the lens on the major axis. Fig. III is a 15 transverse section of the lens on the minor axis.

The leading features of my design consist in a base-lens in the form, approximately, of an ellipse and the approximately circular 20 spherical lens in front of the base-lens and of the diameter of the minor axis of the base-lens, having approximately crescent-shaped surfaces at the ends of the base-lens.

The drawings show an ordinary approximately elliptical base-lens for eyeglasses or 25 spectacles having its periphery formed with a bevel or thin edge, whereby it is held in the frame. In front of this base-lens is a circular spherical lens which is of a diameter equal to the minor axis of the ellipse, so as to extend, as shown in the drawings, in close proximity to the side edges of the base-lens and leave crescent-shaped surfaces at the ends of 30 the lens.

Having thus described my invention, the 35 following is what I claim as new therein and desire to secure by Design Letters Patent:

The design for cataract-lenses for eyeglasses and spectacles substantially as herein shown and described.

PRICE C. CLAFLIN.
